SAFETY CONTROLS FOR ELEVATORS

Bruno A. Wittkuhns, Skaneateles, N.Y., assignor to Hawkeye Products Corporation, Syracuse, N.Y., a corporation of New York

Filed Oct. 11, 1957, Ser. No. 689,602

7 Claims. (Cl. 187—85)

This invention relates broadly to elevator structures, and has particular reference to safety controls for an elevator of the type that can be moved from one location to another for interim use.

In the elevator structure to which the present invention relates, the elevator car is adapted to carry either passengers or materials, but unlike the so-called shaft type elevators the structure can be readily disassembled and re-erected at another site. This mobility or portability of the elevator structure renders it particularly useful for construction, maintenance and repair operations on multi-story buildings or the like, and the structure can also be used as a permanent installation, if desired.

The elevator car or cage, which is of cantilever construction, is raised and lowered by a pair of motor actuated cables and is guided during such movement by a single upstanding column which may be of unitary or sectional form. A normally inoperative cam or pawl is mounted on the car, and this pawl is engageable with the fixed column to immediately stop the downward movement of the car should either or both of the cables break, or if one cable should stretch abnormally, or in the event that the speed of the car exceeds a predetermined safe limit. In accordance with the invention, the safety pawl is arranged for actuation by either a cable equalizer device or by a car mounted governor device, as will be explained in detail below in connection with the description of the annexed drawings.

Accordingly, with the foregoing and other considerations in view, it may be stated that the broad objective of the present invention is to provide novel safety controls for an elevator structure of the above described type.

Another important object of the invention is to provide safety controls for an elevator structure of the above described type which are completely reliable in operation and yet are relatively simple in construction.

A further important object of the invention is to provide safety controls for an elevator structure of the above described type which respond almost instantaneously in the event of a failure and are positive in their car stopping action.

A still further important object of the invention is to provide safety controls for an elevator structure of the above described type which are located completely within the car or cage of the elevator.

Still another important object of the invention is to provide novel elevator safety controls which are operable in the event of breakage of either or both of the cables, or of excessive stretching of one of them, or in the event that the elevator car exceeds a predetermined safe speed, whereby one control insures against the failure of the other.

A still further important object of the invention is to provide novel elevator safety control structure which is strong and durable, and yet is relatively inexpensive to manufacture.

A more specific object of the invention is to provide

2

a novel cable attachment means for the elevator car in the form of a cable equalizer device.

Another specific object of the invention is to provide a novel elevator safety control for an elevator car of cantilever construction which control is operable by means of a car mounted governor device.

Other objects and advantages of the invention will become apparent from the following detailed description thereof read in conjunction with the accompanying drawings which illustrate a representative embodiment of the invention for the purpose of disclosure.

In the drawings:

Figure 1 is a fragmentary isometric view of a portion of the elevator car and structural guide member showing the safety controls embodying the invention, parts of the structure being broken away for greater clarity;

Figure 2 is an enlarged side elevation of a portion of a cable equalizer device of the invention;

Figure 3 is an enlarged side elevation of the car safety pawl and operating linkages connected therewith;

Figure 4 is an enlarged top perspective view of a portion of the car mounted governor and the operating linkage actuated thereby; and

Figure 5 is a diagrammatic representation of the cantilever construction of the elevator car and the forces exerted by the car on the guide column.

Having reference now to the drawings, wherein like reference numbers designate the same parts in each of the views, 10 indicates a fragmentary portion of the elevator car platform, the remainder of the car itself being omitted for greater clarity. Mounted on one side of the car, and forming a part thereof, are a pair of confronting channel or C-beams 11 which are spaced apart to provide an enclosure for the control mechanisms to be described.

The car is guided as it is raised and lowered by means of an H-beam 12, one side 14 of which extends into the space between the C-beams of the car where it is engaged on its inner face and edges by a plurality of pairs of oppositely disposed guide rollers 15 secured to the C-beams. The C-beams and platform 10 of the car form a cantilever construction whereby the weight of the car exerts a moment resulting in forces on the H-beam as represented by the arrows 16 of Figure 5. The H-beam is preferably provided in sections which may be bolted or welded together to form a straight, rigid column or monorail extending up to 250 ft. or more in height. For a more detailed description of a bolted monorail and one method of bracing same, reference may be had to Schuchert Patent #2,531,346, assigned by mesne assignments to the assignee of the present application and invention, said patent also disclosing a cantilever type car construction. While the H-beam column is ordinarily vertically disposed for vertical movement of the car, it can also be erected for inclined car movement by slightly modifying the car structure.

The elevator car is raised and lowered by a pair of braided steel cables 17 each of which terminates in a thimble 18 secured to a cable equalizer device mounted on the car. Cables 17 extend upwardly from the car and pass over a sheave or pulley (not shown) mounted at the top of the H-beam column and then extend downwardly on the opposite side of the column to a double grooved drum (not shown) operated by a suitable electric motor.

In accordance with the invention, control means are provided to immediately stop the downward movement of the car if either cable 17 should stretch abnormally or break and to this end, the car is provided with a heavy, toothed cam or pawl 20 which is movable into engagement with the H-beam column to hold the car at the point of engagement. The pawl 20 is rockable on a stub shaft 21 supported at its ends in a pair of spaced, vertical

plates 22 extending between a pair of spaced, horizontal plates 24 secured to the C-beams 11 as shown. The outer, arcuate end of the pawl and the teeth 25 formed thereon are hardened so that when the pawl is rocked in the counter-clockwise direction the first tooth will bite into the softer material of the H-beam column due to the downward motion of the car and will prevent further travel thereof, see Figures 1 and 3.

The pawl 20 is normally held out of engagement with the H-beam column by a means to be presently described, and in this normal position there is a clearance of approximately $\frac{1}{8}$ " between the column and upper toothed edge of the pawl. This clearance is maintained by a spacing roller 27 which is mounted on the car and bears against the inner side 14 of the column just above the pawl, the roller being supported on a shaft 28 and secured to one of the spaced, vertical plates 22. However, in case the clearance becomes greater than the minimum of $\frac{1}{8}$ " due to wear or a slight displacement, the second, third or fourth tooth on the pawl will engage the H-beam column rather than the first tooth.

The cable equalizer device above referred to comprises a pair of arm plates 30 which are pivotally mounted at their midpoints on a block 31 secured to the upper end of a rod or plunger member 32. Pivotally supported between the outer ends of the arm plates 30 are a pair of apertured blocks 34 to which bolts 35 are adjustably secured as by nuts 36. The upper ends of these bolts are threaded into yoke blocks 37 which are secured to the cable thimbles 18 by means of pins 38 as shown in Figures 1 and 2. The structure just described is assembled so that in operation there is equal tension on the cables 17 and the arm plates 30 are held in a substantially horizontal position on blocks 31 by the cables.

The rod or plunger member 32 passes with a slide fit through aligned bores in the horizontal plates 24, and intermediate these plates it passes through a slot or channel 40 formed in the inner end of the pawl 20. Just below the upper plate 24, the rod 32 is threaded and carries a nut 41 which limits the upward movement of the rod against the force of the cables acting thereon. A spring 42 is positioned on the rod between the lower plate 24 and a retaining washer 44 held in position by a nut 45, the spring normally being held in a compressed state by the upward force of the cables. Between the plates 24, the rod is provided with a transversely extending pin 47 which contacts the upper edge of the pawl without pressure when the rod is held in its upper position by the cables as shown in Figure 1.

Mounted on the car above the arm plates 30 is a bar 48 provided with a pair of spaced pins 50 on its lower edge, see Figure 2. If either one of the cables should stretch abnormally or break, as for example, the right hand cable in Figure 2, the other cable will rock the arm plates 30 on the block 31 until they contact one of the pins 50 as shown. The pin contacted then acts as a fulcrum for the plates whereby the upward force of the undamaged cable imparts a downward movement to the block 31 and rod 32 which movement is aided by the compression spring 42. As the rod 32 moves downwardly, the pin 47 thereon rocks the pawl 20 into engagement with the H-beam column and the first tooth of the pawl is positively driven into the column by the downward movement of the car which is thereafter immediately stopped. The above described action thus occurs automatically in the event of abnormal stretching or breakage of either cable, and, in actual embodiments of the invention, a fully loaded car can be stopped within one quarter of an inch of travel after the pawl has been actuated.

In connection with the above described action, it should be pointed out that the safety factor for the cables is such that either cable alone will safely support a loaded car but the safety device is necessary nonetheless so that immediate notice of any damage will be given

and repair work can proceed without delay. The structure described, however, goes beyond the case of damage to just one cable and also makes provision for stopping the car in the unlikely event that both cables should break simultaneously. In such instance, with neither cable exerting any upward force, the rod 32 will simply be moved downwardly under the action of compression spring 42 to actuate the pawl as above described.

The pawl 20 is normally held out of engagement with the H-beam column by means of a linkage which includes a rod 51 pivotally secured at its upper end to the inner bifurcated end of the pawl. This rod extends downwardly from the pawl through a notch 52 in the lower horizontal plate 24 and is pivotally connected at its lower end to a transversely extending lever 54. The lever 54 is rockably connected as at 55 to one of the C-beams 11 and the free end thereof is provided with a pair of spaced pins 57 which form a yoke structure on the lever. This yoke straddles a vertically disposed governor rod 58 which is guided for longitudinal sliding movement by aligned bores in a pair of horizontal bracket plates 60 secured to the right hand C-beam as is best shown in Figure 1.

An open compression spring 62 is positioned on the governor rod 58 between the lower bracket plate 60 and the yoke pins 57 on lever 54. This spring holds the yoke up against a transverse pin 64 through the governor rod and, at the same time, acts through the rod 51 to hold the pawl 20 in its inoperative position as shown in Figure 1. However, it will be apparent that when the pawl is positively rocked in the counter clockwise direction by the rod 32 of the cable equalizer device as previously described, the spring 62 will permit downward movement of the rod 51 and lever 54, the spring 62 simply being compressed by the yoke pins 57 during such movement.

The governor rod 58 forms a part of a linkage between the pawl 20 and a car mounted governor device which will also cause the pawl to be actuated if the speed of the car exceeds a predetermined safe limit. To this end, the lower end of the rod is normally engaged by a latch plate 65 which is adapted to be tripped by the governor to permit actuation of the rod. The latch plate 65 is in the form of a bell crank, and one arm 67 of the crank is positioned beneath a small roller 68 on the lower end of the rod to hold it in the position shown in Figure 1 against the downward bias of a compression spring 70 which is mounted on the rod between a collar 71 secured thereto and the lower bracket plate 61. The latch plate is pivotally mounted on an upstanding bearing pin 72, and the arm 67 thereof is urged into engagement with the rod by means of a coil spring 74.

The governor device of the invention comprises a pair of positively disposed rollers 75 (only one of which is visible in Figure 1) that are respectively journalled in bosses 77 secured to the C-beams 11 of the elevator car. The rollers bear against the inner side 14 of the H-beam column due to the cantilever construction of the car, see Figure 5, and are rotated by the motion of the car relative to the column. Formed integrally with each roller is a gear 78 and these gears mesh with pinions 80 carried on the opposite ends of a shaft 81 journalled in a pair of spaced upstanding plates 82. In between the plates 82, a bevel gear 84 is loosely mounted on the shaft and the back side of this gear is engaged by a conventional friction disc clutch (not shown) secured to the shaft, the clutch being provided to absorb any starting and stopping shock of the car by allowing slippage between the shaft and the bevel gear.

Bevel gear 84 meshes with a bevel pinion 85 on the lower end of a shaft 87 depending from a governor disc 88, the disc shaft being supported by a bearing housing (not shown) mounted on horizontal plate 90 secured to the plates 82. A pair of trip levers 91, Figures 1 and 4, are pivotally mounted on the governor disc 88 as at 92,

and the free ends of these levers are normally retained within the circumferential boundary of the disc by means of tension springs 94 extending between posts 95, 96 on the levers and disc respectively. The tension of springs 94 is factory adjusted so that if the elevator car starts moving downwardly at a speed in excess of a predetermined safe limit the free ends of the trip levers 91 will be moved by centrifugal force out beyond the periphery of the governor disc and one or the other of them will hit the inwardly extending arm 97 of the latch plate 65 causing it to rotate in the clockwise direction against the action of coil spring 74. As is best shown in Figure 4, stops 98 are provided on the governor disc to limit the movement of the trip levers in either direction, the outer stops being located so that the trip levers can move out just far enough to trip the latch plate when the governor disc is rotated in the counter-clockwise direction by the downward movement of the car.

When the latch plate 65 is tripped by the governor and rotated in the clockwise direction, the arm 67 thereof moves out from beneath the governor rod 58 which is immediately moved downwardly under the action of compression spring 70. When the governor rod moves downwardly, the transverse pin 64 on the rod depresses the lever 54 and rod 51 which rocks the pawl 20 into engagement with the H-beam column. This action occurs entirely independently of the cable equalizer device since the latter is not rigidly connected to the pawl and engages it only through the contact pin 57 on the plunger rod 32. It will thus be seen that either of the above described safety controls is operable to actuate the safety pawl independently of the other, and that this is accomplished by the lost-motion connections of the linkages in the form of the various spring and pin arrangements. It will also be apparent that, if for any reason the cable equalizer device should fail to operate, the governor device will immediately actuate the safety pawl in the event that the cable damage results in excessive car speed.

Since the rod 51 and lever 54 are actuated whenever either safety control is operated, means are provided on the lever to stop the electric motor for the cable drum when the pawl is moved into engagement with the H-beam column, so that the drum will not continue to feed the cable after the car has been stopped. To this end, a micro switch 100 for the motor is mounted on the C-beam above the hinged end of the lever, and the downwardly projecting plunger 101 for the switch is engaged by a small disc 102 on the upper end of an adjustable screw 104 passing through the lever. When the lever is held in its upper position as shown in Figure 1 by the spring 62, the disc 102 depresses the plunger so that the motor switch is closed. However, when the lever is rocked downwardly by either the cable equalizer device or the governor device, the disc is moved away from the plunger which moves outwardly of the switch housing and opens the switch.

From the foregoing description it will be apparent that the present invention provides novel and very practical safety controls for an elevator structure of the type described. The controls are completely reliable in operation, and are immediate and positive in stopping all movement of the elevator car. In addition, the controls are compactly arranged within the elevator car structure itself, and the relatively simple construction thereof permits easy assembly, inspection and maintenance.

The invention may be embodied in other specific forms without departing from the spirit or essential characteristics thereof. The embodiment disclosed is therefore to be considered in all respects as illustrative and not restrictive, the scope of the invention being indicated by the appended claims.

What is claimed is:

1. In an elevator structure including a cantilever type elevator car having a pair of cables operable to raise and

lower the car and a fixed, upstanding structural member to guide the car during its movement: a safety device to prevent downward movement of the car in the event of breakage or stretching of either of said cables comprising a toothed safety pawl of hardened material pivotally mounted on said car adjacent said structural member, a first spring means normally holding said pawl out of engagement with said structural member, a plunger member mounted on said car for vertical movement between upper and lower limiting positions, means on said plunger member engaging said pawl, said last-named means being operable against the action of said first spring means to pivot said pawl into engagement with said structural member when said plunger is moved downwardly towards its lower position, a second spring means on said plunger member normally urging the member downwardly towards its lower position, a rocker arm pivotally secured intermediate its ends to the upper end of said plunger member, each of said cables being secured at one end to the ends of said rocker arm, said cables normally holding the arm against rocking movement on said plunger and also holding said plunger member in its upper position against the action of said second spring means, said rocker arm being rocked on said plunger member by either one of said cables upon the breaking or stretching of the other cable, and fulcrum means on said car engaged by said rocker arm when it rocks to cause said plunger member to move downwardly and pivot said safety pawl, said plunger member also being moved downwardly to actuate said pawl in the event of simultaneous breakage of both cables by said second spring means.

2. Elevator structure as defined in claim 1 including a motor to actuate said pair of cables, a normally closed switch for said motor on said elevator car, and means operably connecting said safety pawl and switch to open the latter when the pawl is actuated by said plunger member.

3. Structure of the character described comprising an elevator car having a pair of cables operable to raise and lower the car; a fixed, upstanding structural member to guide said car during its movement; a safety pawl pivotally mounted on said car adjacent said structural member, said pawl being rockable into engagement with said structural member to prevent downward movement of the car; means to actuate said pawl upon the breaking or unequal stretching of said cables; and means to actuate said pawl independently of the cables when said car exceeds a predetermined speed; said first-named means including a plunger member engaging said pawl and operable when actuated to rock the pawl into engagement with said structural member, and a cable attachment element mounted on said plunger member, each of said cables being attached at one of its ends to said attachment element and normally holding it and the plunger member against movement, said plunger member being actuated to operate said safety pawl by the breakage or unequal stretching of said cables; said second-named means including roller elements mounted on said car in engagement with said fixed structural member, a governor mounted on said car driven by said roller elements as the car moves relative to the structural member, linkage means connected to said safety pawl, said linkage means being movable to rock the pawl into engagement with said structural member, latch means on said car normally holding said linkage means against movement, and means on said governor operable to disengage said latch means from said linkage means when said car exceeds a predetermined speed.

4. In an elevator structure including an elevator car having a pair of cables operable to raise and lower the car and a fixed, upstanding structural member to guide the car during movement; a plunger member mounted on said car for vertical movement between upper and lower limiting positions, spring means on said plunger member normally urging it downwardly towards its lower

position, a cable equalizer bar pivotally secured intermediate its ends to the upper end of said plunger member, each of said cables being secured at one of its ends to the ends of said equalizer bar, said cables normally holding said bar in a stationary horizontal position on said plunger member and also holding the member in its upper position against the action of said spring means, said equalizer bar being rocked on said plunger member by either one of said cables upon the breaking or stretching of the other cable, fulcrum means on said car engaged by said equalizer bar when it rocks to cause said plunger member to move downwardly towards its lower position, said plunger member also being moved downwardly in the event of simultaneous breakage or unequal stretching of both of said cables by said spring means, roller elements mounted on said car in engagement with said fixed structural member, a governor mounted on said car and driven by said roller elements as the car moves relative to the structural member, a second plunger member mounted on said car for vertical movement between upper and lower limiting positions, spring means on said second plunger member normally urging it downwardly towards its lower position, latch means on said car normally holding said second plunger member in its upper position against the action of said last-named spring means, means on said governor operable at a predetermined speed of the governor to disengage said latch means from said plunger member to permit downward movement thereof, a toothed safety pawl pivotally mounted on said car adjacent said fixed structural member, said pawl being rockable into engagement with said structural member to prevent downward movement of the car, and means normally holding said pawl out of engagement with said structural member, said first and second plunger members being operably connected to said pawl to move it into engagement with said structural member against the action of said last-named holding means when either of said plunger members is moved downwardly towards its lower position.

5. In an elevator structure including an elevator car of cantilever construction, means to raise and lower said car, and a fixed, upstanding structural member to guide said car during its movement; a safety device to stop the downward movement of said car in the event that the speed of the car exceeds a predetermined safe limit comprising a toothed safety pawl pivotally mounted on said car adjacent said structural member, said pawl being rockable into locking engagement with said structural member, spring means normally holding said pawl out of engagement with said structural member, roller elements mounted on said car in pressure contact with said fixed structural member, a governor mounted on said car and driven by said roller elements as the car moves relative to the

structural member, a governor rod mounted on said car for vertical movement between upper and lower limiting positions, spring means on said rod normally urging it downwardly towards its lower position, means operably connecting said rod and safety pawl to rock the latter into locking engagement with said structural member upon downward movement of the rod, latch means on said car normally holding said rod in its upper position against the action of said rod spring means, and means mounted on said governor operable at a predetermined speed of the car to disengage said latch means from said rod to permit downward movement thereof.

6. Structure as defined in claim 5 including an electric motor to actuate said elevator car raising and lowering means, and a switch for said motor mounted on said car, said switch normally being held in closed position by said governor rod and safety pawl connecting means and being released to its open position when the pawl is actuated by the downward movement of the rod.
- 15 7. In an elevator structure including an elevator car having a pair of cables operable to raise and lower the car and an upstanding structural member to guide the car during movement; a safety device to prevent downward movement of the car in the event of breakage or stretching of either of said cables comprising a safety pawl pivotally mounted on said car adjacent said structural member, means normally holding said pawl out of engagement with said structural member, a plunger member operably connected to said pawl, a rocker element 20 pivotally secured intermediate its ends to said plunger member, each of said cables being secured at one end to the ends of said rocker element and normally holding it against rocking movement on said plunger member, said rocker element being rocked on said plunger element by either one of said cables upon the breaking or stretching of the other cable, independent means on said car engaged by said rocker element when it rocks to cause the element and plunger member to move together and pivot said safety pawl into locking engagement with said structural member, a normally closed electric motor switch on said car, and linkage means operably connecting said safety pawl and switch to open the latter when the pawl is actuated by said plunger member.
- 25 8. In an elevator structure including an elevator car having a pair of cables operable to raise and lower the car and an upstanding structural member to guide the car during movement; a safety device to prevent downward movement of the car in the event of breakage or stretching of either of said cables comprising a safety pawl pivotally mounted on said car adjacent said structural member, means normally holding said pawl out of engagement with said structural member, a plunger member operably connected to said pawl, a rocker element 30 pivotally secured intermediate its ends to said plunger member, each of said cables being secured at one end to the ends of said rocker element and normally holding it against rocking movement on said plunger member, said rocker element being rocked on said plunger element by either one of said cables upon the breaking or stretching of the other cable, independent means on said car engaged by said rocker element when it rocks to cause the element and plunger member to move together and pivot said safety pawl into locking engagement with said structural member, a normally closed electric motor switch on said car, and linkage means operably connecting said safety pawl and switch to open the latter when the pawl is actuated by said plunger member.
- 35 9. In an elevator structure including an elevator car having a pair of cables operable to raise and lower the car and an upstanding structural member to guide the car during movement; a safety device to prevent downward movement of the car in the event of breakage or stretching of either of said cables comprising a safety pawl pivotally mounted on said car adjacent said structural member, means normally holding said pawl out of engagement with said structural member, a plunger member operably connected to said pawl, a rocker element 40 pivotally secured intermediate its ends to said plunger member, each of said cables being secured at one end to the ends of said rocker element and normally holding it against rocking movement on said plunger member, said rocker element being rocked on said plunger element by either one of said cables upon the breaking or stretching of the other cable, independent means on said car engaged by said rocker element when it rocks to cause the element and plunger member to move together and pivot said safety pawl into locking engagement with said structural member, a normally closed electric motor switch on said car, and linkage means operably connecting said safety pawl and switch to open the latter when the pawl is actuated by said plunger member.
- 45 10. In an elevator structure including an elevator car having a pair of cables operable to raise and lower the car and an upstanding structural member to guide the car during movement; a safety device to prevent downward movement of the car in the event of breakage or stretching of either of said cables comprising a safety pawl pivotally mounted on said car adjacent said structural member, means normally holding said pawl out of engagement with said structural member, a plunger member operably connected to said pawl, a rocker element 45 pivotally secured intermediate its ends to said plunger member, each of said cables being secured at one end to the ends of said rocker element and normally holding it against rocking movement on said plunger member, said rocker element being rocked on said plunger element by either one of said cables upon the breaking or stretching of the other cable, independent means on said car engaged by said rocker element when it rocks to cause the element and plunger member to move together and pivot said safety pawl into locking engagement with said structural member, a normally closed electric motor switch on said car, and linkage means operably connecting said safety pawl and switch to open the latter when the pawl is actuated by said plunger member.
